UNITED STATES PATENT OFFICE

CARL OLSEN, OF LYNN, MASSACHUSETTS, ASSIGNOR TO EXCEL TAPING MACHINE CO., OF LYNN, MASSACHUSETTS, A CORPORATION OF MASSACHUSETTS

METHOD AND APPARATUS FOR APPLYING TAPE

Application filed March 7, 1930. Serial No. 434,144.

This invention relates to the application of pressure to, and manipulation of, moving sheet or strip material, and more particularly to a method and apparatus for applying tape in adhesive engagement with a sheet article or the like, such for example as reinforcing tape which is applied to edge and/or seam portions of shoe uppers or the like.

10 In one aspect this invention is directed to the type of machine and way of applying tape which is disclosed in the copending application of Jerome P. Byron, Serial No. 216,702, filed August 31, 1927, and the copending application of Leland K. Butler, Serial No. 331,550, filed January 10, 1929. These copending applications in general show a machine having juxtaposed rolls and tape supplying instrumentalities arranged 20 whereby adhesively coated tape is engaged by a peripheral portion of one of the rolls and supplied to a tape guide adjoining the bite of the rolls. Sheet material is fed between the rolls and pressed thereby into firm adhesive engagement with the tape. The copending application of Leland K. Butler discloses a machine of this same general type in which selectively actuatable mechanism is provided for severing the adhesive tape to 25 permit the rapid application of strips of the tape to successive separate sheet articles such as parts of shoe uppers.

30 My invention aims to facilitate the proper movement of the tape into engagement with the sheet articles under all operating conditions. Thus one object of the present invention is to provide for preventing the undesirable sticking of the uncoated surface of the tape to the peripheral portion of the juxtaposed roll, which is normally effective in feeding it to the bite of the rolls. A machine of this character may ordinarily be employed for applying tape having a permanently tacky, tenaciously adhesive agglutinant to a 35 sheet article. The tape is ordinarily supplied in rolls having convolutions in adhesive engagement with each other and as successive convolutions of the tape are removed from the roll there is a tendency for a portion 40 of the adhesive to cling to the uncoated

surface of the tape, and hence for the tape undesirably to adhere to the peripheral portion of the roll. Wetting of the uncoated surface of the tape effectively prevents such a phenomenon and permits the proper frictional engagement of the tape with the peripheral portion of the roll without undesirable sticking thereof.

45 The present invention provides for rapidly varying the amount of pressure applied to the sheet material being taped or otherwise operated upon. Preferably a vibratory movement is imparted to one of the rolls, which movement may desirably have an amplitude of an order less than that of the thickness of the sheet material fed between the rolls, so that the gripping effect of the rolls is rapidly varied, although under normal operating conditions a substantially continuous frictional engagement of greater or less intensity is maintained between the rolls and the interposed sheet article and tape. This is particularly advantageous in permitting the turning of the sheet article in relation to the tape, thus for example permitting the application of the reinforcing tape to a curved edge portion of the sheet article. The rapidly varying intensity of the gripping pressure permits the turning or movement of the sheet article in relation to the rollers without substantially preventing the constant and substantially uniform application of the tape or feeding of the sheet article; thus tape may be easily and smoothly applied to a sheet article in a curved line without puckering or uneven stretching.

50 Preferably provision is made for varying the amplitude of vibratory movement to permit the machine most effectively to operate upon material of different thicknesses and in different classes of work. These desirable results are preferably obtained by providing a cam having a plurality of throws of minute height for causing rapid and slight vibratory movement of one of the rolls, and a cooperating follower assembly which is adjustable to permit variation of even this small amplitude of movement.

55 A further feature of the present invention is an arrangement of the operating instru- 100

5 mentalities of a coating device, whereby these operating instrumentalities are advantageously disposed and enclosed, and thus rendered less likely to interfere with sheet material being operated on in various positions, or with the easy accessibility of the operator to the machine.

10 Other objects and advantages of my invention will be apparent from this explanation of a specific instance of my invention 10 illustrated by the accompanying drawings, in which:

15 Fig. 1 is a front end elevation of a taping machine embodying my invention;

15 Fig. 2 is a side elevation of the device of Fig. 1;

20 Fig. 3 is a section on the line 3—3 of Fig. 2, 20 illustrative of part of the mechanism employed in automatically and periodically relieving the pressure of the opposed rolls of the device;

25 Fig. 4 is a rear end elevation of the device with the operating pulley and hand wheel partly broken away, and showing the arrangement of driving gears normally concealed by this pulley and hand wheel;

30 Fig. 5 is a fragmentary side elevation of the side of the device from opposite to that shown in Fig. 2, and with the pulley and hand wheel removed;

35 Figs. 6 and 6^a are sections on the line 6—6 of Fig. 2, Fig. 6 showing the tape guiding and presenting mechanism of the device in position for the cooperating pressure rolls 35 to advance the tape and apply it to sheet material interposed between the rolls, and Fig. 6^a showing the pivoted guide-actuating arm of the device and the retained tape guide swung to a position wherein the tape may be 40 cut, and showing the tape cutting instrumentality projected for severing the tape;

45 Fig. 7 is a fragmentary plan view showing parts of the pivotally mounted guide retaining arm, one member of its associated tape guide, and the pressure roll adjacent which the tape guide moves;

50 Fig. 8 is a top plan view of a detachable and interchangeable part of the tape guide;

55 Fig. 9 is a bottom plan view of the part of the tape guide shown in Fig. 8;

Fig. 10 is a section on the line 10—10 of Fig. 8; and

Fig. 11 is a fragmentary section on the line 11—11 of Fig. 2.

55 In the illustrated embodiment of my invention, referring to Fig. 1, adhesive tape indicated by the reference character 11 may be applied from a closely wound roll 12 supported by any suitable bracket 13. The pressure applying device, which includes the two opposed pressure rolls 14 and 15, preferably driven at approximately the same peripheral speed, serves to withdraw the tape from the roll of tape in the manner disclosed in the 65 copending applications referred to above, the

tape passing over a pulley 16, thence partially around the periphery of the lower pressure roll 15 over a tape tensioning or take-up roll 17 retained on a pivotally mounted and outwardly spring-pressed arm 18, thence farther around the periphery of the lower pressure roll 15 and through suitable tape guiding instrumentalities which in the normal taping operation, indicated in Figs. 1 and 6, present the tape to the bite of the juxtaposed pressure rolls. Sheet material indicated generally by the letter S may be fed between the pressure rolls, and the tape 11 thus progressively applied to its under side. Accordingly the adhesive tape is fed to the device so that its adhesively coated side is outward as it passes around the periphery of the lower pressure roller 15 toward the bite of the rolls. 70

The frictional engagement of the tape with the periphery of the roll before passing to the 75 guiding means is chiefly effective in drawing the tape run from the roll 12 so that the tape as supplied to the bite of the rolls is substantially free of tension. Adhesively coated tape withdrawn from a tightly wound roll is 80 somewhat adhesive on its uncoated face and normally would exhibit a tendency to adhere to and be advanced by the pressure roll 15 after having been severed, at which time it is 85 desirable that feeding of the tape be suspended. To avoid such difficulty of overfeeding of the tape after severance, I prefer to reduce somewhat the adhesiveness of the uncoated face of the tape prior to its contacting with the pressure roll 15 by interposing a moistening device, such as indicated in Fig. 1 by the reference numeral 20, between the supply of adhesive tape and this pressure roll. In the 90 illustrated embodiment of my invention this moistening device 20 comprises an inverted 95 channel element with a top and depending side guiding the moving tape and pivoted at 100 105 110 115 wardly extending arm 32 (Fig. 5) pivoted at 33 to the base 30. As shown in Fig. 11, a tongue 150 projects from the lower or base part 30 of the casing and is engaged by opposite sides 151 of a slot in the movable frame or head, thus to retain the movable frame in alignment with the base, while allowing vertical movement of the movable frame about the pivot 33.

- 10 The lower pressure roll 15 is mounted, as shown in Fig. 2, upon an upwardly extending part 35' of a hollow extension 35 of the base, while upper pressure roll 14 is similarly mounted upon a downwardly extending part 36' of a hollow extension 36 of the movable frame 31. In this way a relatively large open space indicated in Fig. 2 by the reference character A is provided for the passage or manipulation of sheet material when desired.
- 15 To augment the effect of gravity in forcing the upper roller 14 toward the lower roller 15, I have provided a coil spring 120 for reacting upon the movable frame 31 to force it, together with its roller 14, toward the base and roller 15. Referring to Fig. 2, the upper end of spring 120 engages a part 121 of the base and its lower end engages a nut 122 threaded on a rod 123 which extends through the movable frame 31. Rod 123 is rotatably mounted
- 20 in a bearing 124 in the movable frame and a hand wheel 125 and a collar 126 on the rod prevents vertical movement of the rod relative to the head. The pressure thus applied by the spring 120 to the opposed rollers may be varied by rotating the hand wheel 125, thus turning the rod 123 relative to the nut 122 and causing the nut, which is restrained against rotation by the sliding engagement of a forked extension 127 with a fixed rod 128, to travel up or down and either compress or relieve the spring.

To permit the upper movable frame 31 to be selectively raised for the easy insertion of sheet material between the rolls or for any other purpose, I have provided a lever 130 pivoted at 131 to the base, and adapted to bear upwardly at one end against a collar 132 fixed on the rod 123 and to raise the rod 123, the movable frame and the upper pressure roller.

45 The opposite end of the lever 130 is connected to an operating rod 134 which may be connected to any suitable treadle, not shown, to permit the operator of the device to raise the movable frame by foot actuation.

50 A main shaft 37 retained in suitable bearings in the base 30 is keyed to a combined hand wheel and pulley 38 which serves to receive power from any suitable source. Referring to Fig. 4, wherein this hand wheel and pulley 38 is not shown, the reference symbol 38' indicates an axially disposed pinion forming part of the hand wheel and pulley and which serves to transmit the rotary movement of the hand wheel

55 and pulley to the various automatically

actuated parts of the device. Pinion 38' meshes with a gear wheel 39 which carries a pinion 40 meshing in turn with a gear wheel 41 keyed to a horizontal shaft 42 (see also Fig. 2) which extends lengthwise of the device through the hollow base and drives the lower pressure roll 15 through intermeshing gears 43 and 44 (Fig. 1). Referring again to Fig. 4, gear wheel 41 acting through gear wheels 47, 48 and 49 also drives a horizontal shaft 50 (see also Fig. 2) which extends forwardly through the hollow upper head or frame of the device, and, as shown in Fig. 1, drives the upper pressure roller through intermeshing gear wheels 52 and 53. 80 Preferably the number and sizes of the driving gear wheels employed is such that the opposed rollers 14 and 15 will rotate at, or approximately at, the same peripheral speed. Referring to Fig. 4 it will be noted that the uppermost gear wheels 48 and 49 at the rear end of the device are retained by the movable frame 31, with the other gear wheels below these two are axially fixed with respect to the base 30 of the device; however, the pivot 33 is substantially in the planes of these gears so that the slight swinging movement of head 31 does not appreciably affect their intermeshed engagement.

The inner end of main shaft 37 carries cam 60 (Figs. 2 and 3) which serves automatically to relieve (preferably only partially) the pressure applied by the opposed rollers to the sheet material operated on, thus to permit the sheet material to be turned while between the rolls. This cam 60 has a contour preferably approximating that of a cylinder disposed axially of the shaft 37, but having around its periphery slightly flattened portions 61, of which eight are shown in the present embodiment. Thus, the throw of the cam is relatively small, and the rapidity of the vibrations which the cam is capable of imparting is quite high.

Referring to Fig. 3 a follower member 110 comprising an arm 62 is pivoted to the base portion 30 of the device at 63 and carries a roller 64 adjacent its outer end and in contact with the cam surface. An abutment member 66 pivoted to the upper movable frame 31 at 67 and bearing upwardly against an adjusting screw 68 engages the upper surface of the cam follower 62, whereby rotary movement of the cam 60 is adapted to cause vertical oscillation of the movable frame 31 and rapidly and periodically to relieve the pressure exerted by the upper pressure roller 14 upon the sheet material passing between the two pressure rollers. By utilizing a cam having relative small throws 120 and capable of causing rapid oscillation of the movable frame 31, the feeding of material between the pressure rollers is not rendered discontinuous but the pressure may merely be rapidly relieved sufficiently to per-

mit turning of sheet material interposed between the rolls. Preferably and as will be apparent from an inspection of the various gears shown in Figs. 4 and 1, the driving gears connecting the cam 60 with the pressure rolls comprise reduction gearing, the cam 60 rotating much faster than the pressure rolls. I prefer that the number of throws per revolution of the cam, the gear ratio of the gears connecting the cam and the pressure rolls, and the diameters of the pressure rolls be proportioned to provide an oscillation of the upper roll for each very small linear distance of advance of the sheet material. For example in the illustrated embodiment, the upper roll oscillates once during each approximately one-seventh inch of advance of the sheet material. Thus in operating on a sheet of material of some slight compressibility, such for example as a sheet of leather, the distance of advance of the sheet material during a given cycle of increase and reduction of pressure by the rolls may be, and preferably is, less than the length of sheet material contacted thereby at the time of application of maximum pressure. Accordingly a close approach toward uniformity of compression of all parts of the strip thus acted on is obtained. With this advantage of approach to uniformity of compression, the capability of ready turning of the sheet material relative to the rolls is also attained.

An accurate adjustment of the amount of oscillation of the movable head 31, and hence the extent to which pressure of the rolls is periodically and almost instantaneously relieved, may be obtained by means of the adjusting screw 68. Since the upper pressure roll 14 normally bears upon the sheet material disposed between the rollers, obviously the extent to which pressure is relieved, may be adjusted by turning the screw 68 to permit the abutment member 66 to rise slightly from the position shown in Fig. 3 thereby ordinarily utilizing only a portion of the throws of the cam 60 for displacing the movable frame to relieve the pressure. Continued movement of the adjusting screw 68 sufficient to prevent the transmission of force from the eccentric follower to the upper movable frame 31 allows the upper pressure roller to bear with constant pressure upon the sheet material interposed between the rollers. This adjustment of the device may be preferable when the sheet material being fed between the rolls need not be turned, as for example when the tape is to be fed to a straight edge or seam of the sheet article.

The feeding and cutting mechanism associated with the lower roll 15, and which is of the general type described and claimed in the copending application of Leland K. Butler referred to above, comprises in addition to the idler roll 16 and tension roll 17, a pivotally

mounted arm 70 movable about the axis of pressure roller 15 and carrying at one end tape guiding parts, and at its opposite end a spring-retained dog for operating the cutting instrumentality.

Referring to Figs. 6, 6^a, and 7 to 10, this pivotally mounted arm 70 carries at one extremity a lower tape guide 71 having a slot 72 (Fig. 7), adjacent its free end and pivotally mounted upon a pin 73 retained by the swinging arm 70. A suitable coil spring 74 bearing upon the extremity of the pivoted arm 70, passing around the pin 73 and connected to the tape guide 71, serves to urge the tape guide toward the periphery of the adjacent roller 15. An upper tape guide 77, shown separately in Figs. 8 to 10 inclusive, comprises a metallic strip having one end turned back on itself, as shown at 78, with opposite edge portions 79 of this turned-over part bent down to engage the side surface of the pressure roll 15, (see Fig. 6), and having a slot 80 in its turned-over part, adjacent its end. As shown in Fig. 6, the tape guide 77 is retained upon the lower tape guide 71 by means of pins 85 attached to the latter and extending up through holes 85' in the former, and by a threaded stub bolt 87 carried by the lower tape guide extending through a slot 88 in the tape guide 77 and carrying a detachable nut 89 which serves securely to clamp the two tape guides together while permitting detachment of the forward tape guide at will. With this construction, the slotted tape guide 77 may easily be removed and another similar tape guide be substituted having, for example, a tape-feeding slot 80 of different width.

A tape catch 90 which prevents backward motion of the tape during swinging of the tape guides, is also pivotally mounted upon the pin 73, bears at its serrated free end 91 upon the tape passing around the periphery of the lower roller 15, and is yieldably pressed thereagainst by a part of the spring member 74, as shown in Fig. 7.

The opposite end of the pivoted arm 70 carries a dog 92 pivoted thereto at 100, and normally retained by a spring 93 against the stop pin 94. A fixed bracket 95 disposed between the pivotally mounted arm 70 and the roller 15 carries a detachably mounted knife casing 96 containing a slidable knife carrier 97 normally retracted by a spring 103, and having a knife 99 at its outer end adjacent the path of the moving tape. The rear end of the knife carrier 97 is provided with a striker element 101 which may conveniently comprise the head of a screw held in adjusted relation to the carrier by a nut 102. Striker 101 is so positioned in relation to the upper end of the dog 92 that it is engaged thereby when the dog moves upwardly in response to a swinging movement of the pivoted arm 70 in the direction of the arrow in Fig. 6, and is moved by the dog to cause the knife carrier 103

97 to project the knife 99 into the path of the tape, as indicated in Fig. 6^a. Referring to Fig. 6^a which shows the pivoted arm 70 near the end of its swinging movement, it 5 will be noted that further swinging movement of the arm in the direction of the arrow will serve to disengage the dog 92 from the striker 101 and permit the knife 99 to be retracted from its cutting position by the 10 spring 103.

Referring to Fig. 6, it will be seen that during the application of tape by the device, the tape guide 77 positions the tape closely adjacent to the point of application of pressure 15 by the opposed rollers 14 and 15, the tape guide 72 retains the tape above and out of contact with the serrated edge of the knife 99, while the tape catch 90 bears upon the tape being fed to the two tape guides. In swinging 20 the pivoted arm 70 to cause the dog 92 to actuate the cutting knife 99, the two tape guides and the tape catch are simultaneously, and in advance of severance of the tape by the knife, swung partially around the periphery 25 of the roller 15 in the opposite direction to the direction of motion of the tape, and entirely out of the path of the knife. During this backward movement of the tape guides, the tape catch 90 drags upon the tape and prevents 30 it from being drawn back by the tape guides. In the tape cutting position of Fig. 6^a, the two tape guides engage the tape below the knife so that after severance of the tape and return of the tape guides to the tape 35 applying position of Fig. 6 the free end of the tape will be presented by the tape guide 77 to a position between the pressure rolls for further feeding of tape. It may be observed 40 here that the cutting knife 99 does not necessarily sever the tape by chopping action alone, but is aided in cutting the tape by the forward pull of the tape with respect to the knife by the cooperating pressure rollers 14 and 15.

45 For the purpose of actuating the pivoted arm 70 to cause these cooperating movements of the tape guide and cutting knife, I provide an improved operating mechanism which may be mainly contained within the hollow 50 base 30 of the device and hence does not obstruct the freedom of movement of material or interfere with the operator of the device. Referring to Fig. 6, a sector gear 105 intermeshes with corresponding gear teeth 106 on the pivoted arm 70. The shaft 107 (see also 55 Fig. 2) mounted in suitable bearings in the base of the device extends rearwardly through the base, is adapted to oscillate this sector gear 105 to swing the pivot arm 70. A lever arm 108 rigidly affixed to shaft 107 is connected to a suitable vertical operating rod 109 which may be connected to any suitable treadle, by means of which the operator 60 of the device may actuate the cutting instrumentality.

I claim:

1. Apparatus of the class described comprising a pair of juxtaposed rolls, driving means therefor to cause the rolls to have substantially the same peripheral speed, means 70 yieldably urging the rolls toward each other, vibratory means for varying the exact juxtaposition of the rolls, and a guide for directing a strip between the rolls, whereby a sheet article fed into contact with the strip 75 between the rolls may be readily turned.

2. Apparatus of the class described comprising a pair of juxtaposed rolls, means for feeding tape between the rolls, a swinging frame supporting one of the rolls and its 80 drive shaft, a spring connected to the swinging frame yieldably urging the rolls, toward each other, and a cam and follower to cooperate with the spring to cause a vibratory movement of the frame and the roll supported 85 thereby.

3. Apparatus for the class described comprising juxtaposed rolls for progressively applying pressure to sheet material fed therebetween, and means for relieving the pressure 90 thus exerted a plurality of times during each revolution of one of the rolls.

4. Apparatus of the class described comprising juxtaposed rolls arranged progressively to apply pressure to sheet material fed therebetween, means for automatically and periodically moving one of the rolls away from the other roll during rotation thereof, thereby to relieve the pressure on the sheet 95 material at frequent intervals and facilitate 100 turning of the sheet material with respect to said rolls.

5. Apparatus of the class described comprising opposed rolls arranged progressively to apply pressure to sheet material fed therebetween, means for feeding tape between the 105 rollers in position to be pressed by the rolls into adhesive engagement with the sheet material, and means for moving one of the rolls away from the other roll a plurality of times 110 during each revolution of one of the rolls.

6. Apparatus of the class described comprising a base, a movable head, a pressure roll mounted on said base, a shaft for driving said roll, a second pressure roll retained by 115 said movable head in juxtaposition to said first-named pressure roll, a shaft in said movable head for driving said second roll, spring means for forcing said movable head toward said base thereby to cause said rolls to exert 120 pressure upon sheet material interposed between said rolls, cam means for automatically and periodically forcing said movable head away from said base thereby to relieve the pressure exerted by the rolls, and drive gear interconnecting said two shafts and said cam means.

7. Apparatus of the class described comprising a base, a movable head, a pressure roll retained by said base, a second pressure roll 125

retained by said movable head in opposition to said first-named pressure roll, spring means for forcing said movable head toward said base thereby to cause said rolls to exert pressure upon sheet material interposed between said rolls, a cam revolvably mounted on said base, a follower mounted to contact with said cam, means carried by the movable head for contacting with said follower to cause the follower periodically to force the movable head away from the base thereby to relieve the pressure of the rolls upon the interposed material, and drive gearing interconnecting said two pressure rolls and said cam.

8. Apparatus of the class described comprising juxtaposed pressure rolls, means for forcing said rolls together to apply rolling pressure to sheet material interposed therebetween, cam means for automatically moving one of said rolls away from the other roll during rotation thereof to relieve pressure on the interposed sheet material, and adjustable means for determining the amount of movement thus effected.

9. Apparatus of the class described comprising juxtaposed pressure rolls, means for forcing said rolls together to apply rolling pressure to sheet material interposed therebetween, cam means for automatically moving one of said rolls away from the other roll a plurality of times during a revolution of one of said rolls, and means for selectively rendering said cam means effective or ineffective.

10. Apparatus of the class described comprising a hollow frame, pressure rolls supported by said frame and disposed to receive sheet material therebetween, means for feeding tape through a path generally conforming to the periphery of one of said rolls and between the rolls, cutting means movable into the path of the tape for severing the tape, a pivoted arm and a tape guide carried thereby normally between said cutting means and the point of opposition of said rolls and movable by swinging of said arm to the opposite side of said cutting means, sector gear teeth associated with said pivoted arm adjacent its pivot point, a sector gear meshing with said teeth, an oscillating shaft extending laterally through the frame for actuating said sector gear.

11. Apparatus of the class described comprising juxtaposed pressure rolls, means for guiding adhesive tape through a path generally conforming to the periphery of one of the rolls to present the tape to the compressive action of the rolls, thereby to affix the tape to sheet material interposed between the rolls, and means for moistening the tape prior to its contacting with the roll around which it travels, thereby to prevent sticking of adhesive coating upon the tape to the said roll.

12. In a machine of the type having a pair of juxtaposed pressure-applying rolls which

are normally yieldably urged toward each other, driving mechanism to effect the rotation of the rolls at substantially the same peripheral speeds, a support for one of the rolls relatively movable in relation to the other roll, a fixed frame for the other roll, driving mechanism for the rolls, and a shaft mounted upon the frame and having a portion in eccentric relation to its axis of rotation, means associated with said portion and with the movable support to vary the relative position of the support and corresponding roll with respect to the frame and the roll supported thereby, whereby a relative vibratory effect is imparted to the rolls as they rotate at substantially the same peripheral speed.

13. A machine of the class described comprising a lower frame portion, an upper frame portion having a limited swinging movement in relation to the lower frame portion, a roll carried by each of said frame portions, driving mechanism for said rolls arranged to effect their movement at substantially the same peripheral speeds, a shaft having a portion in eccentric relation to its axis and motion-transmitting means disposed between the eccentric portion of said shaft and the swinging frame member whereby vibratory movement may be imparted to the frame member and the corresponding roll when the driving mechanism is operated.

14. Method of pressing sheets in adhesive engagement with each other, which comprises, continuously moving the sheets between pressure applying elements and continuously moving the portions of the elements which contact the sheet in the direction of sheet movement while rapidly vibrating the elements in relation to each other thereby causing rapid fluctuation of the imposed pressure.

15. Method of pressing sheets in adhesive engagement with each other, which comprises continuously moving the sheets between pressure applying elements and continuously moving the portions of the elements which contact the sheet in the direction of sheet movement while rapidly vibrating the elements in relation to each other and so controlling the amplitude of vibration that pressure of varying amount is continuously being applied to the sheets.

16. Method of pressing sheets in adhesive engagement with each other, which comprises continuously moving the sheets between pressure applying elements and continuously moving the portions of the elements which contact the sheet in the direction of sheet movement while rapidly vibrating the elements in relation to each other and so controlling the frequency of vibration in relation to the rate of sheet movement and the yieldability thereof under the maximum imposed pressure that one complete vibration occurs during a time of the order of that required

for the movement of a given point on a moving sheet through the area of contact as determined by maximum compression.

17. Apparatus of the class described comprising a base, a movable head, a pressure roll mounted on said base, a shaft for driving said roll, a second pressure roll retained by said movable head in juxtaposition to said first-named pressure roll, a shaft in said movable head for driving said second roll, spring means for forcing said movable head toward said base thereby to cause said rolls to exert pressure upon sheet material interposed between said rolls, drive means for rotating said rolls at substantially the same peripheral speed, a rotatable cam, means associated with the drive means and the cam for rotating the latter at speed substantially higher than that of the rolls, and follower means associated with the cam and head causing the latter and the roll supported thereby rapidly to be vibrated in relation to the base and the roll carried thereby.

18. Apparatus of the class described comprising a base, a movable head, a pressure roll mounted on said base, a shaft for driving said roll, a second pressure roll retained by said movable head in juxtaposition to said first-named pressure roll, a shaft in said movable head for driving said second roll, a spring means for forcing said movable head toward said base thereby to cause said rolls to exert pressure upon sheet material interposed between said rolls, drive means for rotating said rolls at substantially the same peripheral speed, a rotatable cam, means associated with the drive means and the cam for rotating the latter at speed substantially higher than that of the rolls, a swinging member carried upon said base and having a roller engaging the cam, and an abutment member mounted upon the head to engage the swinging member, said abutment member being adjustably mounted to vary the vibratory movement imparted to the head by the cam.

Signed by me at Lynn, Mass., this first day of March, 1930.

CARL OLSEN.
